(57) **CLAIM**

The ornamental design for a particle prevention adapter, as shown and described.

DESCRIPTION

FIG. 1 is a top front perspective view of a particle prevention adapter, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the design that form no part of the claim. The shade lines in the drawings show contour and not surface ornamentation of the claimed design.
